UNITED STATES PATENT OFFICE.

JOHN H. BURKE AND OTTO A. WILMING, OF WILLITS, CALIFORNIA.

SANITARY MEAT-CASE.

1,129,635.

Specification of Letters Patent. Patented Feb. 23, 1915.

Application filed April 25, 1913. Serial No. 763,599.

To all whom it may concern:

Be it known that we, JOHN H. BURKE and OTTO A. WILMING, citizens of the United States, residing at Willits, in the county of 5 Mendocino and State of California, have invented new and useful Improvements in Sanitary Meat-Cases, of which the following is a specification.

This invention relates to an improvement 10 in cases for hams, bacon, and the like, in the use of which the contents may be hermetically sealed to prevent deterioration and loss of weight by evaporation under indefinite storage.

15 The main object of the present invention is the provision of cases in which the articles may be indefinitely preserved and readily removed. The details of the structure provide for the convenient handling of the case 20 and the contained article and the utilization of the supporting means as a medium for opening the case.

25 The invention in its preferred form of details will be described in the following specification, reference being had particularly to the accompanying drawings, in which:—

30 Figure 1 is a perspective view illustrating the improved case. Fig. 2 is a transverse section thereof. Fig. 3 is a detail sectional view.

Referring particularly to the accompanying drawings, the improved case, which is preferably constructed of light metal, is made up in two approximately duplicate 35 sections 1 and 2 shaped so that when fitted together they will form a case corresponding generally to the shape of the article which said case is to contain. The sections are assembled after the article has been 40 wrapped in suitable wrapping paper and placed therein with their free edges in contact, and a binding or sealing strip 3 is arranged to overlie the edges and to be soldered to or otherwise removably secured in 45 place so as to seal the juncture of the edges. At the upper end the sealing strip 3 has its terminals spaced from the case sections and formed to present eyes or loops 4, an auxiliary sealing strip 5 being used to close the 50 joints between the sections throughout that portion of such joint not covered by the sealing strip 3. A handle or carrying member is provided, made up of approximately dupli-

cate sections 6 which are preferably semi-cylindrical and designed when in handle 55 forming relation to have their flat sides in contact and to be secured in such manner by cords or other flexible fasteners 7 seated in grooves 8 formed in the handle section. Comparatively rigid connectors as wires 9 60 are mounted in each handle section, projecting beyond the ends thereof and being turned downwardly to engage the loops 4 of the sealing strip. If desired each connector 9 may be formed with a single length of wire 65 passed through the eyes 4 of the sealing strip with its ends secured in the handle or passed lengthwise through the handle section with the ends secured in the loop. When in place with the sections connected the article contained in the case is subjected to the action of heat, a small relief opening 10 formed in one of the sections permitting the escape of the gases driven off by the heat, said opening being hermetically sealed while the contained article is still heated considerable 70 above normal. In completed form the case may be readily handled through the medium of the handle and stored as desired, it being obvious that the hermetic sealing described 75 will prevent deterioration of the contained article without regard to the length of time the same remains in storage. When it is desired to use the contained article the handle sections are separated by removing the 80 fasteners 7 and the handle used to tear the sealing strip 3 from its juncture with the section, thereby freeing the sections throughout practically their full extent so that they may be readily separated and the contents 85 removed. It is to be understood of course that the case is to be shaped in accordance with the article which it is used to contain.

What is claimed is:—

1. A case made up of sections arranged 95 edge to edge, a strip overlying the edges and sealed in place, the ends of the strip being formed to provide eyes and handle means connected to the eyes to provide for carrying the case, said means being adapted for disrupting the sealing strip.

2. A storage case comprising metallic sections arranged edge to edge, a sealing strip overlying the abutting edges and sealed to the respective sections, the terminals of the 100 strip being spaced from the sections, a han- 105

dle member comprising independent sec-
tions, means for securing said sections in
handle forming relation, connections be-
tween the respective sections and projecting
5 ends of the sealing strip, and an auxiliary
sealing strip overlying the joint of the sec-
tions between the free end of the first men-
tioned sealing strip.

In testimony whereof we affix our signa-
tures in presence of two witnesses.

JOHN H. BURKE.
OTTO A. WILMING.
